UNITED STATES PATENT OFFICE.

MINOR EUGENE TYNES, OF GLOSTER, MISSISSIPPI.

SEWING-MACHINE ATTACHMENT.

1,249,560.

Specification of Letters Patent. Patented Dec. 11, 1917.

Application filed February 23, 1917. Serial No. 150,541.

To all whom it may concern:

Be it known that I, MINOR E. TYNES, a citizen of the United States, residing at Gloster, in the county of Amite and State 5 of Mississippi, have invented a new and useful Sewing-Machine Attachment, of which the following is a specification.

The device forming the subject matter of this application is adapted to be attached 10 to the needle bar of a sewing machine, for the purpose of facilitating embroidery operations, and the invention aims to provide a device of this kind, which, being fashioned from a single piece of resilient wire, 15 is so constructed that the material which is being embroidered will not be drawn, novel means being provided whereby the embroidery thread will be kept in a loose condition.

With the above and other objects in view 20 which will appear as the description proceeds, the invention resides in the combination and arrangement of parts and in the details of construction hereinafter described and claimed, it being understood that changes 25 in the precise embodiment of the invention herein disclosed can be made within the scope of what is claimed, without departing from the spirit of the invention.

In the accompanying drawings:—

30 Figure 1 is a perspective showing the attachment applied to a sewing machine; and Fig. 2 is a top plan of the attachment.

The embroidery attachment forming the subject matter of this application is fashioned from a single piece of resilient wire 35 bent at 1 to form a V-shaped horizontal foot comprising arms of unequal lengths, the shorter arm 2 terminating in an upstanding finger 3 having a thread-receiving eye 4, the longer arm 5 being flexed as shown at 40 to form an overhanging resilient extension 7. The extension 7 is bent upon itself intermediate its ends to fashion a thread-receiving eye 8, the extension being bent 45 upon itself to define a needle-receiving eye 9 located between the arms 2—5 of the foot when the attachment is viewed in top plan. The constituent material of the eye 9 is extended to form a strip 20 disposed above 50 and at an angle to the short arm 2 of the foot and terminating in an eye 11, the constituent material of which is extended to form an upstanding hook 21.

The needle bar of a sewing machine is shown at 12, and the needle appears at 14. 55 The needle 14 passes through the eye 9 and because the eye 9 is located between the arms 2—5 of the foot when the attachment is viewed in top plan, the needle can work between the arms 2—5 of the foot. The 60 hook 11 is engaged with the set screw 15 which holds the needle 14 in the bar 12. The numeral 16 indicates the embroidery thread. The thread is passed through the eye 8 of the extension 7, and through the 65 eye 4, and finally through the eye of the needle. In practical operation, the extension 7 and its eye may move upwardly and downwardly, and in this way, the thread is kept loose, and the material which is being 70 embroidered cannot be drawn.

Having thus described the invention, what is claimed is:—

An embroidery attachment for sewing machines, fashioned from a single piece of 75 resilient wire bent to form a V-shaped horizontal foot comprising rearwardly extended arms of unequal lengths, the shorter arm terminating at its rear end in an upstanding finger provided at its upper end with a 80 thread-receiving eye, the longer arm being flexed forwardly to form an overhanging resilient extension, the said extension being bent upon itself intermediate its forward and rear ends to fashion a thread-receiving 85 eye complementary to the eye of the finger, the extension being bent upon itself at its forward end to define a needle receiving eye located between the arms of the foot when the attachment is viewed in top plan, 90 the constituent material of the last specified eye being extended to form a strip disposed above and at an angle to the short arm of the foot and terminating in an upstanding means for engaging the set screw on the 95 needle bar of a sewing machine.

In testimony that I claim the foregoing as my own, I have hereto affixed my signature in the presence of two witnesses.

MINOR EUGENE TYNES.
